(57) **CLAIM**

We claim the ornamental design for a portable electronic device with cover, as shown and described.

DESCRIPTION

FIG. 1 is a front perspective view of a portable electronic device with cover showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an exploded front view thereof in which the side portion is shown separated from the portable electronic device with cover;

FIG. 10 is an enlarged view of the encircled portion shown in FIG. 3;

FIG. 11 is an enlarged view of the encircled portion shown in FIG. 4; and,

FIG. 12 is an enlarged view of the encircled portion shown in FIG. 6.

The short dash-dash broken line in the figures shows portions of portable electronic device with cover which form no part of the claimed design. The dot-dot-dash broken line encircling portions of the claimed design that are illustrated in enlargements form no part of the claimed design.
